UNITED STATES PATENT OFFICE.

HOMER ADDAMS, OF OSWEGO, NEW YORK.

BOILER.

Application filed July 1, 1926. Serial No. 119,817.

This invention relates in general to boilers and more particularly to boilers having two passes of flues.

Among the objects of the present invention, it is aimed to provide a new construction of boiler in which for a given fire grate area or combustion surface, the space occupied by the flues relative to the fire box is very compact, so that a much smaller space 10 is occupied by the boiler proper, giving a much wider range of use for this type of boiler and at the same time enhancing the efficiency of the boiler from the standpoint of cost of construction and cost of upkeep for a 15 given work capacity.

It is further aimed to provide an improved construction for boilers in general.

These and other features, capabilities and advantages of the invention will appear from 20 the subjoined detail description of one specific embodiment thereof illustrated in the accompanying drawings, in which

Figure 1 is a plan of a boiler made according to the present invention.

Fig. 2 is a section substantially on the line 25 2-2 of Fig. 1.

Fig. 3 is a front elevation.

The boiler consists essentially of a front main portion A and a rear extension B, the 30 outline of the rear extension being substantially oblong, the upper curved surface of which being merely a continuation of the upper curved surface of the front portion A, the outline of the lower end of the front portion 35 A being substantially rectangular as shown in Fig. 3.

The boiler has an outer shell consisting of a front plate 1 provided with an opening 2 for the fire door and provided with a chimney 40 extension 3 above said fire door, a second main plate, the inverted U-shaped plate 5 which is riveted to the front plate 1 at 4 and extends from the lower end of one side of the portion A and continues up and into the curved part 45 6 of the portion A and then continues down the other side of the portion A to the bottom thereof, a third main plate 7 formed in the outline of the curved wall of the portion B and riveted to the upper curved part 6 of the plate 5 at 8, and a fourth plate 9 substantially plane in surface and having an upper recessed portion to receive the plate 7 and riveted to the plate 7 at 10 and to the plate 5 at 11. The plates 5 and 7 may be made of one 55 continuous plate but are preferably made separate and attached to one another as

shown. The rear end of the portion B is provided with a suitable closure member 12. The inner shells or wall members of the furnace are preferably welded to the outer shell 60 member and to one another as now to be described and constitute an important part of the present invention.

Spaced from and substantially parallel to the closure 12 there is provided a plate 13 which is welded throughout its periphery to the plate 7, and is provided with openings to receive the flue pipes 14 and 15. The plate 1, registering with the chimney portions 3, is provided with suitable openings 16 to receive the outlet ends of the upper flue pipes 15. The flue pipes 15 are thus secured to the plate 1 and the plate 13 and supported thereby to afford access between the chamber 17 formed between the closure 12 and the plate 75 13, and the chimney portion 3.

The inner wall 18 of the fire box 19 is spaced from the plate 1, the plate 9 and the plate 6 to form a water jacket for the fire box. The inner wall 18 has a front plate 20 which is welded around the opening 2 to the plate 1, and has a second plate 21, a third plate 22 and a fourth plate 23 which are welded to one another at their adjacent edges as illustrated in Fig. 2. The plate 21 extends from the bottom of one side of the fire box, one part thereof, being U-shaped, continuing over the front or high portion H of the fire box 19 and down to the lower end of the other side of the fire box 19, and the rear parts 24 of the plate 21 90 merely extending up to the plate 23 and being there welded to such plate. It will be seen that the plate 21 of the fire box 19 is recessed to receive the plate 22 to form an L-shape in side elevation. The plate 22 has a lower 95 horizontal part 25 and continuing therefrom upwardly an upper vertical part 26. By this means the upper portion of the fire box will have a diminished front part H, the plate 22 virtually extending into the fire box 19 to 100 close off the upper rear part thereof. By this means it will be seen that the lower part of the fire box 19 will be left intact in order to afford an extended fire grate area or combustion surface and the upper portion H constricted. The vertical section 26 of the plate 22 is provided with a plurality of openings 27 to receive the front ends of the lower flue pipes 14. Thus it will be seen that the flue pipes 14 will be supported at their front ends 110 by the plate 22 and at their rear ends by the plate 13. It will thus also be seen that the

- front portions of the flue pipes 14 where they receive the hot gases of combustion from the fire chamber will have not only their inlet portions exposed to the fire chamber but also 5 will have a substantial length of them extending into the area arbitrarily designated as 28 and over the rear portion of the fire box. The area 28 is that portion of the boiler formed by the bent plate 22.
- 10 The plate 7 is provided with an opening 29 serving as the inlet for the water to the water chamber W. The plate 7 is also provided with a steam outlet 30. The plate 5 is provided with a manhole 31 and a safety valve 15 opening 32. The plate 9 at the lower end thereof adjacent to the lower end of the plate 23 is provided with a blow-off or drain opening 33.

It may also be desirable to supply suitable 20 stays 35 connecting the plate 21 and the horizontal part 25 of the plate 22 with the curved part 6 of the plate 5. Suitable stays 36 may also be provided to connect the sides of the plate 5 and the plate 7 with one another properly 25 to brace the same. Furthermore, in some cases it may also be desirable to provide stays 37 connecting the vertical part 22 of the plate 21 with the plate 9, as indicated in Fig. 1.

In the operation of this boiler, the gases 30 of combustion will pass through the sheet 22 into the flue pipes 14 and out through the rear ends thereof into the chamber 17 and from there through the shield 13 into the flue pipes 15 and out through the front end of the flue 35 pipes 15 into the chimney member 3.

From the foregoing it will be seen that the section 25 of the plate 22 will be heated by the fire grate to heat the area 28 of the chamber W, and also directly heat the plate 21 to heat 40 the area 34 of the chamber W, above the plate 21, and at the same time supply the hot gases for the flue pipes 14, the construction of the fire box serving to secure intimate intermingling of the gases from the fire with 45 the oxygen of the air, thus attaining more perfect combustion and increasing their temperature prior to their passage through the flue pipes, 14, and thus securing more effective transfer of heat from the gases to the 50 water surrounding the flue pipes and the fire box.

By means of the foregoing, it will also be seen that by forming the area 28 and thus extending the front ends of the flue pipes 14 a 55 substantial distance into the fire box 19, for a given fire grate area and the consequent flue pipe area, with a two-pass boiler the length of the boiler is materially decreased. In other words, with a two-pass boiler having 60 flue pipes 14 going one way and flue pipes 15 directing the hot gases in the opposite direction, in order to obtain the same flue pipe heating surface, the boiler would have to be considerably longer, at least one-half of the 65 length of the part 25 of the section 22. In

other words, if merely a one-pass boiler were used, merely having the flue pipes 14 extending in one direction in order to obtain the same heating surface of flue pipe, without the area 28, the boiler would have to be longer by a 70 distance equal about to the length of the area 28 or the part 25 of the plate 22. In view of the fact, however, that the areas 28 and 34 are disposed directly above and substantially in 75 intimate contact with the fire box, experience has taught that for a given efficiency the flue pipes can be diminished still further as compared to a boiler in which the front ends of the flue pipes do not extend into the fire box.

It has also been found that by forming the 80 constricted portion H, thereby increasing the temperature of the gases fed up into such constricted area resulting in an increased rate of heat transfer through the walls of the flue pipes as compared to a similar boiler without 85 such constricted chamber, a substantially less surface of flue pipe is required to obtain a given heating result.

It is furthermore to be noted from the construction above described that by welding the 90 joints of the inner wall a decidedly cheaper construction can be produced without impairing the efficiency or longevity of the boiler.

From the foregoing it will also be seen that, 95 since the water enters into the portion B to the right of the fire box, the coolest area will be that indicated generally by the reference character 38, and the hottest heating area, the area designated 28, due to its proximity to the fire box and also to its contact with the 100 hottest portion of flue pipes, to wit the entering portions of the flue pipes 14; that the second hottest area will be the area 34 directly above the constricted chamber portion H of the fire box and that the third hottest portion 105 of the chamber W, or the second coolest portion of the chamber W will be the area designated generally by the reference character 39. By these successive areas of varying temperature graduating one into the other in 110 order, a free circulation of the water is effected, to wit from the coolest area 38 to the hottest area 28 and then upward to the next succeeding area 34 less hot than the area 28, and then laterally rearward to the next area 115 39 less hot than the area 34 and then back to the coolest area 38.

It is of course obvious that certain changes and modifications may be made to the details of construction without departing from the 120 general spirit of the invention as set forth in the appended claims.

I claim:

1. In a steam boiler, the combination with a firebox rectangular in horizontal cross section and having an upper constricted extension at its front end, of a fire door formed in the front end of said firebox, a housing, a shield mounted in said housing and spaced a short distance from the rear end of said hous- 125

- ing to form a return chamber for the flue gases between said rear end and said shield and a water reservoir to the front thereof, the lower portion of the housing extending from the rear face of the constricted extension of said firebox and across and beyond the rear end of the firebox, the upper portion of the housing extending across the top of the constricted extension of the firebox, a lower group of flue pipes extending through the lower portion of said housing from the rear face of said constricted extension to said shield to form communication between the firebox and the return chamber, a second group of flue pipes extending through the upper portion of said housing from the shield to the front end of said housing, and a chimney member in communication with the front end of said upper group of flue pipes.
2. In a steam boiler, the combination with a firebox rectangular in horizontal cross section and having an upper constricted extension at its front end, of a fire door formed in the front end of said firebox, a housing, a shield mounted in said housing and spaced a short distance from the rear end of said housing to form a return chamber for the flue gases between said rear end and said shield and a water reservoir to the front thereof, the lower portion of the housing extending from the rear face of the constricted extension of said firebox and across and beyond the rear end of the firebox, the upper portion of the housing extending across the top of the constricted extension of the firebox, a lower group of flue pipes extending through the lower portion of said housing from the rear face of said constricted extension to said shield to form communication between the firebox and the return chamber, a second group of flue pipes extending through the upper portion of said housing from the shield to the front end of said housing, a water inlet in the bottom of said housing to the rear of said firebox, and a steam outlet in the top of said housing to the rear of said firebox.
3. In a steam boiler, the combination with a housing comprising a main outer shell portion having a downward extension rectangular in horizontal cross section and a rear tubular outer shell extension riveted to the rear upper end of said main outer shell portion, of an inner shell in said main outer shell portion having a constricted portion at its upper end to form a fire-box having an upper constricted extension at its front end and forming with the main outer shell portion a water jacket along the sides of the lower portion of said fire-box, a shield mounted in said housing and spaced a short distance from the rear end of said tubular extension to form a return chamber for the flue gases between said rear end and said shield and to form a water reservoir to the front of said shield, a lower group of flue pipes extending through the lower portion of said housing from the rear face of said constricted extension to said shield to form communication between the firebox and the return chamber, a second group of flue pipes extending through the upper portion of said housing from the shield to the front end of said main outer shell, and a chimney member in communication with the front end of said upper group of flue pipes.
4. In a steam boiler, the combination with an outer shell having a curved rearward portion, a main inverted U-shaped plate, a plane front plate and a plane intermediate recessed plate, the plane front plate being riveted to the front edge of the inverted U-shaped plate, the upper curved part of the inverted U-shaped plate being riveted to the upper curved part of the rearward portion and the recessed plate being riveted both to the inverted U-shaped plate and to the rearward portion to connect the two and form an outer shell having a front downward extension rectangular in horizontal cross section; a door for the rear end of the rearward portion; a shield spaced from the door and welded to the rearward portion to form a return chamber; an inner wall forming a firebox and a water jacket for the firebox with the downward extension of the outer shell, the inner wall having an inverted U-shaped plate recessed at its rear upper end to simulate an L-shape, a front plate welded to the front edge of the inverted U-shaped plate of the inner wall also having a rear plate welded to the rear edges of the inverted U-shaped plate, and also having a bent plate welded to the edges of the recessed portion of its inverted U-shaped plate; a fire door formed in the front plates of the outer shell and inner wall; a group of flue pipes extending from the bent plate of the inner wall to the shield to afford communication between the fire box and the return chamber; and a second group of flue pipes extending from the shield to the front plate of the outer shell and affording communication between the return chamber and the atmosphere, the curved rearward portion and main inverted U-shaped plate forming a steam chamber above, and the full length of, the second group of flue pipes.
5. In a steam boiler, the combination with a water reservoir having a steam chamber above and the full length thereof, a lower group of flue pipes passing therethrough to convey the flue gases therethrough in one direction, an upper group of flue pipes extending through said water reservoir to conduct the flue gases through said reservoir in the opposite direction to the direction of the flue gases in the lower group, there being a communication between said lower group of flue pipes and said upper group of flue pipes to permit the flue gases from the lower group to pass into the upper group, a water inlet

at the bottom of the rear portion of the reservoir, a fire box rectangular in horizontal cross section under the lower part of the front portion of the reservoir, a fire door in the front end of the firebox, the portion of the reservoir containing the front ends of the lower group of flue pipes extending into, and above the rear end of the fire box to form an intensive heating area, and the portion of the reservoir containing the outlet ends of the upper group of flue pipes disposed above the

upper end of the fire box to form a less intensive heating area, whereby the cool water from the water inlet will be caused to pass to the intensive heating area of the reservoir, then to the less intensive heating area of the reservoir and then rearward through the upper portion of the reservoir back to the lower portion of the reservoir to effect a free circulation of the water. ¹⁵

HOMER ADDAMS.
